(57) **CLAIM**

The ornamental design for a kettle, as shown and described.

DESCRIPTION

FIG. 1 is a front perspective view of a kettle incorporating the design of the present invention;

FIG. 2 is a rear perspective view of the kettle of FIG. 1; and,
FIG. 3 is a side elevational view thereof.

The bottom of the kettle of FIG. 1 is flat and unornamented.

1 Claim, 3 Drawing Sheets

FIG. 1

FIG. 2

FIG. 3
